UNITED STATES PATENT OFFICE.

WILEY T. RABUN, OF INGLEWOOD, CALIFORNIA.

DESIGN FOR AN ARM FOR BRIDGE LAMPS.

Application filed September 21, 1927. Serial No. 23,486. Term of patent 3½ years.

To all whom it may concern:

Be it known that I, WILEY T. RABUN, a citizen of the United States, residing at Inglewood, in the county of Los Angeles and State of California, have invented a new, original, and ornamental Design for an Arm for Bridge Lamps, of which the following is a specification, reference being had to the accompanying drawing, forming part thereof.

In the drawing,

Fig. 1 is a face view, and

Fig. 2 is a rear view of the design for an arm for bridge lamps.

I claim:

The ornamental design for an arm for bridge lamps, as shown.

WILEY T. RABUN.
